STRUCTURAL BLOCK

Jeremiah J. O'Leary, Buffalo, N. Y.

Application October 27, 1938, Serial No. 237,289

14 Claims. (Cl. 72—41)

This invention relates to structural blocks and, although not necessarily limited to, is concerned primarily with a block of cellular construction.

One object of the invention is to provide a block which is weather-proof and which has high heat insulating properties.

A still further object is a block which is so constructed that the inner face may have a finishing surface such as, for example, paint or plaster applied directly to it and thereby avoid the necessity of furring, this object contemplating a cellular arrangement which will provide a passage for the circulation of air and the drainage of any water which may seep into or condense in the block.

A still further object is to provide a block which is so reinforced as to enable the construction of walls which, with respect to a particular thickness, have high strength factors.

A still further object is a block which may be mechanically connected with the adjacent blocks in a wall in such a manner that expansion and contraction of the wall is permitted under changing weather conditions without the formation of cracks or widening of the joints.

A still further object is to provide for facility and accuracy in the laying of the block.

A still further object is a block in which provision is made for securing the insulating material against displacement.

The invention is illustrated in the accompanying drawings in which:

Figure 1 is a side elevation of a portion of a wall constructed from blocks embodying the features of the invention.

Figures 2 and 3 are perspective views of one of the blocks.

Figure 4 is a perspective view of the bat of insulating material which is arranged in the inner cell 40 of the block.

Figure 5 is a horizontal section through the wall and is taken along line 5—5 of Figure 1.

Figure 6 is a vertical section taken along line 6—6 of Figure 5.

Figure 7 is a longitudinal section taken along line 7—7 of Figure 5.

The block, which is molded, may be formed of any suitable composition and the inner and outer faces, indicated at 10 and 11, respectively, may be finished in any desired manner. As illustrated, the inner face is finished plain while the outer face is scored as at 12 to simulate brick, it being understood in this connection that the dimensions of the block, although variable, are preferably such that the brick representations may be full

size. Longitudinally extending ribs 13 and 14 are formed on the top of the block while similarly spaced grooves 15 and 16 are formed on the bottom, one end of the rib 13 connecting with a vertical rib 17 formed on one end of the block 5 while the opposite end of the rib 14 connects with a vertical rib 18 formed on the opposite end of the block. In a like manner one end of the groove 15 connects with a vertical groove 19 formed in one end of the block while the opposite end of 10 the groove 16 connects with a similar groove 20 formed in the opposite end of the block. It will be apparent, therefore, that while two ribs are formed on the top of the block and two grooves on the bottom, each end is formed with one rib 15 and one groove, the block being so formed that each of the ribs 13 and 14 connects with a vertical rib at one end of the block and a vertical groove at the opposite end. It is understood, of course, that the grooves on the under side of the 20 block are adapted to accommodate adjacent portions of the ribs on the upper side of two lower blocks, the arrangement of the ribs and grooves in the manner described having the advantage that they will match while permitting end for 25 end turning of the block.

The invention contemplates the laying of the blocks in courses in conventional manner, each block being arranged so that its central portion is located over the joint provided by the abutting ends 30 of the two blocks upon which it rests. In order to mechanically connect the blocks each carries a pair of prongs 21 which project a substantial distance below the bottom wall. The prongs, as shown, constitute the legs of a U-shaped member 35 22 which is embedded in and arranged crosswise of the block midway between its ends. Sockets 23 are formed in the vertical ribs 17 and 18 of the block to accommodate the prongs of the upper blocks, the said sockets preferably being reinforced by metal sleeves 24. Referring to Figure 40 5, it will be noted that (with respect to each joint) a vertical rib 17 of one block fits in a vertical groove 19 of an adjacent block while a rib 18 of the latter fits in a groove 20 of the former. When a block 45 in the next course is laid upon these two blocks in the manner described, one of the prongs 21 will enter a socket in one of the blocks while the other will enter a socket in the other of the blocks. Each upper block, therefore, is mechanically connected to each of the two lower blocks. Preferably the prongs 21 are smaller in diameter than the sockets in which they fit in order to permit 50 expansion and contraction of the wall under changing weather conditions. Provision may be 55

made in this manner for movement of a predetermined magnitude between adjacent blocks. As the wall expands or contracts, therefore, the maximum movement of each block is predetermined and is so limited as to prevent the formation of cracks or excessive widening of the joints, the latter preferably being sealed with mortar 25 in conventional manner. Each block is permitted to move in the manner described. Hence, although movement of the individual blocks is limited, ample provision is made, considering the wall as a whole, for such expansion or contraction as may take place.

The U-shaped member 22 ties together the web and front and rear walls of the block. As a result of this and the connection of the blocks by the prongs of the members 22, a wall of great strength is insured. The construction described, therefore, has the advantage that it enables the building of walls of considerably less thickness than would otherwise be possible.

The block is preferably hollow and is formed with a central web 26 which provides inner and outer chambers 27 and 28, respectively. The said chambers extend through and lengthwise of the block. Referring to Figure 7, it will be noted that owing to the construction of a wall in the manner described the chamber 28 of each block communicates with the corresponding chambers 30 of the two lower blocks and the corresponding chambers of the two upper blocks, thereby providing vertical air passages through the wall. In this connection it is to be understood that in the construction of the wall the lowermost course of blocks will be supported in such a manner that air will be permitted to enter the air passages thus provided and that provision will likewise be made to permit such air to escape through the blocks of the top course. It will be apparent, therefore, that the circulation of air through the outer chambers of the blocks will carry away any cold or damp air which may enter them and will thus tend to prevent condensation of water in the chambers. If, however, any condensation should occur or water should seep through the outer walls into these chambers it will drain off through the passages provided by them. Penetration of water to the inner chambers 27 of the blocks is thus prevented.

Each end wall of the block is formed with a channel 28a. The latter is adapted to cooperate with a corresponding channel in an end of an adjacent block to provide a drain passage to carry away any water which may enter the joint between the blocks. The passages thus provided communicate with the outer chambers 28 of adjacent blocks. Hence any water entering the said passages will drain off through the said chambers.

The inner chamber 27 of the block is filled with a suitable insulating material 29. The latter, as best shown in Figure 4, is in the form of a bat and is formed with a centrally located slit 30 so that as it is inserted in the chamber 27 its ends will straddle the cross-piece 31 of the U-shaped member 22, the material at the inner end of the slit engaging the cross-piece to secure the bat in the desired position. The insulating material in the inner chamber seals the latter and prevents heat from being dissipated through the block.

From the foregoing it will be apparent that the seepage of water or the penetration of moist air to the inner face of the block is prevented. The finishing surface for the said face may, therefore,

be applied directly to the block thereby rendering the use of furring unnecessary.

I claim as my invention:

1. A structural block having a rib and groove formed at each end, the positions of the rib and groove at one end being reversed with respect to the positions of the rib and groove at the opposite end, sockets formed in said ribs and means carried by said block and located centrally with respect to the ends thereof for insertion in the 10 sockets in the ribs of the adjacent ends of a pair of blocks, whereby to connect said block mechanically to said last named blocks.

2. A structural block having a rib and a groove formed at each end, the positions of the rib and groove at one end being reversed with respect to the positions of the rib and groove at the opposite end, sockets formed in said ribs and prongs carried by said block, said prongs occupying a vertical plane which is transverse with respect 20 to the length of the block and being located centrally with respect to the ends thereof for insertion in the sockets in the ribs of the adjacent ends of a pair of blocks, whereby to connect said block mechanically to said last named blocks. 25

3. A structural block having a rib and a groove formed at each end, the position of the rib and groove at one end being reversed with respect to the positions of the rib and groove at the opposite end, sockets formed in said ribs and a U- 30 shaped element carried by said block, said element being arranged crosswise of the block and reinforcing the latter in such direction, being located centrally with respect to the ends thereof, and having legs for insertion in the sockets in the 35 ribs of the adjacent ends of a pair of blocks, whereby to connect said block mechanically to said last named blocks.

4. A structural block having a pair of ribs formed on its upper side and a pair of grooves 40 formed in its under side, one of said ribs and one of said grooves having continuations formed on one end of the block and the other of said ribs and the other of said grooves having continuations formed on the other end of said block, the 45 positions of the rib and groove continuations at one end of the block being reversed with respect to the positions of the rib and groove continuations at the opposite end, sockets formed in said rib continuations and means carried by said block 50 and located centrally with respect to the ends thereof for insertion in the sockets in the rib of the adjacent ends of a pair of blocks, whereby to connect said block mechanically to said last named blocks. 55

5. A structural block having a pair of ribs formed on its upper side and a pair of grooves formed in its under side, one of said ribs and one of said grooves having continuations formed on one end of the block and the other of said ribs 60 and the other of said grooves having continuations formed on the other end of said block, the positions of the rib and groove continuations at one end of the block being reversed with respect 65 to the positions of the rib and groove continuations at the opposite end, sockets formed in said rib continuations and prongs carried by said block, said prongs occupying a vertical plane which is transverse with respect to the length of 70 the block and being located centrally with respect to ends thereof for insertion in the sockets in the ribs of the adjacent ends of a pair of blocks, whereby to connect said block mechanically to said last named blocks. 75

6. A hollow structural block having a rib and a groove formed on each end, the positions of the rib and groove at one end being reversed with respect to the positions of the rib and groove at the opposite end, sockets formed in said ribs and means cast in the side walls of said block to provide crosswise reinforcement and located centrally with respect to the ends thereof for insertion in the sockets in the ribs of the adjacent ends of a pair of blocks, whereby to connect said block mechanically to said last named blocks.

7. A hollow structural block having a pair of ribs formed on its upper side and a pair of grooves formed in its under side, one of said ribs and one of said grooves having continuations formed on one end of the block and the other of said ribs and the other of said grooves having continuations formed on the other end of said block, the positions of the rib and groove continuations at one end of the block being reversed with respect to the rib and groove continuations at the opposite end, sockets formed in said rib continuations, a U-shaped element cast 25 in the side walls of said block to provide crosswise reinforcement and located centrally of the ends thereof, said element having legs for insertion in the sockets in the ribs of the adjacent ends of a pair of blocks, whereby to connect said block mechanically to said last named blocks.

8. A hollow structural block having a rib and groove formed on each end, the positions of the rib and groove at one end being reversed with respect to the positions of the rib and groove at the opposite end, sockets formed in said ribs, a U-shaped element cast in said block, said element being arranged crosswise of the block and reinforcing the latter in such direction, being located centrally with respect to the ends thereof, and having legs for insertion in the sockets in the ribs of the adjacent ends of a pair of blocks, whereby to connect said block mechanically to said last named blocks and insulating material secured in said block by said element.

9. A hollow structural block having a rib and groove formed on each end, the positions of the rib and groove at one end being reversed with respect to the rib and groove at the opposite end, sockets formed in said ribs, a U-shaped element cast in said block, said element being arranged crosswise of the block and reinforcing the latter in such direction, being located centrally with respect to the ends thereof, and having legs for insertion in the sockets in the ribs of the adjacent ends of a pair of blocks, whereby to connect said block mechanically to said last named blocks and a bat of insulating material in said block, said bat being slit to divide it into sections which straddle said element, the material at the end of said slit engaging said element to secure the bat in said block.

10. A hollow structural block having a lengthwise extending web dividing the interior into inner and outer chambers, said block having a rib and groove formed on each end, the positions of the rib and groove at one end being reversed with respect to the positions of the rib and groove at the opposite end, sockets formed in said ribs, a U-shaped element cast in said block, said element passing through said web and connecting the inner and outer walls of the block to provide crosswise reinforcement, being located centrally with respect to the ends of the block, and having legs for insertion in the sockets in the ribs of the adjacent ends of a pair of blocks, whereby

to connect said block mechanically to said last named blocks and insulating material secured in said inner chamber by said element.

11. A hollow structural block having a lengthwise extending web dividing the interior into inner and outer chambers, said block having a pair of ribs formed on its upper side and a pair of grooves formed in its under side, one of the said ribs and one of said grooves having continuations formed on one end of the block and the other of said ribs and the other of said grooves having continuations formed on the other end of said block, the positions of the rib and groove continuations at one end of the block being reversed with respect to the positions of the rib and groove continuations at the opposite end, sockets formed in said rib continuations, means carried by said block and located centrally with respect to the ends thereof for insertion in the sockets in the ribs of the adjacent ends of a pair of blocks, whereby to connect said block mechanically to said last named blocks and insulating material secured in said inner chamber by said means.

12. A hollow structural block having a lengthwise extending web dividing the interior into inner and outer chambers, said block having a pair of ribs formed on its upper side and a pair of grooves formed in its under side, one of said ribs and one of said grooves having continuations formed on one end of the block and the other of said ribs and the other of said grooves having continuations formed on the other end of said block, the positions of the rib and groove continuations at one end of the block being reversed with respect to the positions of the rib and groove continuations at the opposite end, sockets formed in said rib continuations, a U-shaped element cast in said block, said element passing through said web and connecting the inner and outer walls of the block to provide crosswise reinforcement, being located centrally with respect to the ends of the block, and having legs for insertion in the sockets in the ribs of the adjacent ends of a pair of blocks, whereby to connect said block mechanically with said last named blocks and insulating material secured in said inner chamber by said element.

13. A structural block having a rib and a groove formed on each end, the positions of the rib and groove at one end being reversed with respect to the positions of the rib and groove at the opposite end, sockets formed in said ribs, means carried by said block and located centrally with respect to the ends thereof for insertion in the sockets in the ribs of the adjacent ends of a pair of blocks, whereby to connect said block mechanically to said last named blocks and drainage channels formed in the ends of said block between said ribs and grooves.

14. A hollow structural block having a lengthwise extending web dividing the interior into inner and outer channels, said block having a pair of ribs formed on its upper side and a pair of grooves formed in its under side, one of said ribs and one of said grooves having continuations formed on one end of the block and the other of said ribs and the other of said grooves having continuations formed on the other end of said block, the positions of the rib and groove continuations at one end of the block being reversed with respect to the positions of the rib and groove continuations at the opposite end, sockets formed in said rib continuations, a U-shaped element cast in said block, said element passing through

said web and connecting the inner and outer walls of the block to provide crosswise reinforcement, being located centrally with respect to the ends of the block, and having legs for insertion in the sockets in the ribs of the adjacent ends of a pair of blocks, whereby to connect said block

mechanically with said last named blocks, drainage channels formed in the ends of the block between the rib and groove continuations and insulating material secured in said inner chamber by said element.

JEREMIAH J. O'LEARY.
